ZINC SULFAMATE ANTIPERSPIRANT

Lester D. Apperson, Convent Station, N. J., assignor to Colgate-Palmolive-Peet Company, Jersey City, N. J., a corporation of Delaware

No Drawing. Application May 3, 1949,
Serial No. 91,217

4 Claims. (Cl. 167—90)

1

This invention relates to cosmetic astringent compositions and more particularly to improvements in anti-perspirant preparations.

Among the many anti-perspirants described as having the property of retarding or inhibiting the flow of perspiration the most effective have been found heretofore to be those containing polyvalent metal salts of strong inorganic acids, e. g. hydrochloric, sulfuric, etc. Cosmetic preparations containing salts of these strong acids, however, have the very serious disadvantage of being corrosive to clothing fabric, e. g., portions of garments which come in contact with areas of the body on which the preparation is applied. This corrosive action is especially noticeable on fabrics containing cellulosic materials such as cotton, rayon and the like. The corrosive effect that is detrimental to fabrics manifests itself particularly where the clothing portion carrying some of the anti-perspirant material is ironed or otherwise subjected to a relatively high temperature before removal of the anti-perspirant preparation. Even long continued contact at ordinary temperature of cosmetic preparations containing salts of these mineral acids cause weakening or deterioration of the clothing fabric.

Of the many salts which have been proposed for use as anti-perspirants, aluminum chloride and aluminum sulfate are by far the most commonly used and have heretofore been considered to be the most effective. However, both salts show high corrosive action on cotton fabrics. This corrosive action is so severe that considerable research and investigation has been directed to a satisfactory reduction of the corrosive action without simultaneously reducing the anti-perspirant effectiveness of the salts. Because of its less corrosive action, aluminum sulfate is generally preferred over aluminum chloride.

It has now been discovered that zinc sulfamate is a very efficacious perspiration retardant and, more significantly, it has been observed to have practically no tendering or discoloring action on clothing fabric. Test data have further indicated that zinc sulfamate preparations produce definitely superior results in inhibiting or retarding perspiration when compared with like preparations which contain aluminum sulfate.

To secure such data, specific areas of skin of a number of human subjects were treated daily over a definite period and the perspiration inhibiting effects for aluminum sulfate and zinc sulfamate were evaluated. The perspiration from equal comparable areas of skin with and without anti-perspirant treatment was periodically collected and weighed. For each measurement a per cent of perspiration-lessening effect

2

was found by dividing the number representing the difference between the weight of perspiration on an untreated area and the weight of perspiration on a like area treated with anti-perspirant material by the weight of perspiration on the untreated area, and then multiplying the quotient obtained by one hundred.

The results obtained from the tests showed that zinc sulfamate was from two to four or more times as effective as aluminum sulfate when comparable concentrations were used. In addition there is the important advantage that zinc sulfamate does not cause discoloration and has a very low tendering-action on fabric, antiperspirant preparations containing zinc sulfamate as an astringent may be used without the addition of corrosion or discoloration inhibiting agents.

In accordance with the present invention, the novel perspiration inhibiting or retarding preparation comprises essentially zinc sulfamate as the anti-perspirant ingredient and water and preferably an additional agent to provide a product having certain desirable properties. The anti-perspirant preparation may be prepared and marketed in any desired form, for example as an emulsion, suspension, solution, salve, cream, lotion, and the like, and they may be compounded in any suitable manner.

The proportion of zinc sulfamate to the total composition may be rather widely varied and depends to some extent upon the particular type of preparation, frequency of use, preferred concentration and other variable factors. In general, a composition should contain sufficient zinc sulfamate to be effective when the usual amount of the preparation is applied to the skin and no more should be present than can be held in solution in the aqueous phase. Satisfactory results may be obtained in compositions in which the proportionate quantity of zinc sulfamate incorporated ranges between about 5% and 60% by weight of the anti-perspirant preparation, and preferably comprises about 10 to 30% by weight.

The additional agent comprises one or more materials for imparting desirable properties to the preparation including a wetting agent to facilitate application of the preparation to the skin; pigment; filler; emollient; preservative; perfume; fatty material to form an oily phase for cream, salve, emulsion and like types of preparations; etc.

Zinc sulfamate may be incorporated into cream bases of widely varying composition. Generally speaking, such a cream includes an oily or oleaginous phase held in dispersion in an aqueous phase containing the anti-perspirant by one or more suitable emulsifying agents. The oily phase

may include such materials as natural and synthetic oils, fats and waxes, e. g. spermaceti, palmityl palmitate, polymerized ethylene oxide ("Carbowax"), paraffin, sterols, mineral oils, vegetable oils and other esters of fatty acids, etc. Glyceriné, propylene glycol, sorbitol and the like emollients may also be present.

Any suitable emulsifying agent may be employed which is sufficiently stable in acid media. Examples of emulsifying agents which have been found useful in preparing creams are: partial esters of fatty acids with glycerine, glycol or other polyhydric alcohol, preferably in combination with a stabilizer such as sodium monosulfate monoglyceride or coconut oil fatty acids, diethyloleylamide phosphate, sodium lauryl sulfate, sodium alkyl aromatic sulfonate, etc.

As specific examples of preparations embodying the principles of this invention the following are given without intending to be limited thereby. The parts indicated are by weight.

Example 1

	Parts
Acid stabilized glyceryl monostearate ¹	15.0
Spermaceti wax	5.0
Sodium lauryl sulfate	1.5
Titanium dioxide	0.5
Zinc sulfamate	16.0
Water	55.0

¹ Acid stabilized glyceryl monostearate comprises glyceryl monostearate and a small amount (2 to 5% by wt.) of diethyloleylamid phosphate.

Example 2

	Parts
Diethylene glycol monostearate	15.0
Spermaceti wax	5.0
Glycerine	1.0
Sodium salt of sulfated monoglyceride of coconut oil fatty acids	2.5
Titanium dioxide	0.5
Zinc sulfamate	15.0
Water	54.0

Example 3

	Parts
Glyceryl palmitate	15.0
Palmityl palmitate	3.0
Glycerine	2.0
Sodium salt of sulfated monoglyceride of coconut oil fatty acids	3.0
Titanium dioxide	0.5
Zinc sulfamate	14.0
Water	50.0

Example 4

	Parts
Acid stabilized glyceryl monostearate	12.0
Spermaceti wax	3.0
Stearyl alcohol	2.0
Sodium β -oleylethane-amidsulfonate (Igepon T)	3.0
Glycerine	2.5
Zinc sulfamate	22.5
Water	56.0

Example 5

	Parts
Glyceryl monostearate	12.0
Spermaceti wax	4.0
Glycerine	2.5
Sodium salt of sulfated monoglyceride of hydrogenated coconut oil fatty acids	2.5
Titanium dioxide	0.8
Zinc sulfamate	25.0
Water	53.0

Examples of suitable zinc sulfamate anti-perspirant solutions which may be used in liquid form as a lotion or as the water phase in a cream or emulsion-type preparation, such as described in Examples 1 to 5, are as follows, the parts being by weight:

Example 6

	Parts
Zinc sulfamate	16.0
Sodium salt of sulfated monoglyceride of coconut oil fatty acids	1.5
Water	32.5

Example 7

	Parts
Zinc sulfamate	16.0
Sodium lauryl sulfate	1.5
Water	32.5

Example 8

	Parts
Zinc sulfamate	16.0
Sodium β -oleylethane-amidsulfonate	1.5

Water

In compounding the anti-perspirant solutions exemplified by Examples 6, 7 and 8, other suitable materials may be present or used in place of the surface-active materials described. For example, effective amounts of glycerine, fatty material, perfume, water-soluble salts, or mixtures thereof, may be incorporated which do not cause precipitation of the zinc sulfamate or otherwise adversely affect the anti-perspirant properties of the preparation.

Aqueous solutions of zinc sulfamate suitable for use in compounding the anti-perspirant compositions of the invention may be prepared by appropriate methods, such as by reacting an equivalent amount of sulfamic acid in water with zinc oxide to give a solution of zinc sulfamate. Another method which may be used comprises the reaction of barium sulfamate in an aqueous medium with an equivalent amount of zinc sulfate to form insoluble barium sulfate which may be removed to leave a clear solution of zinc sulfamate. Aqueous solutions also may be prepared directly from the salt. A suitable salt which may be used for this purpose consists of zinc sulfamate crystals containing four moles of water per mole of zinc sulfamate.

Although the invention has been described in detail and exemplified by a number of examples, it will be understood that the principles of the invention may be made use of by utilizing zinc sulfamate with modified formulae such as will occur to those skilled in the art.

What is claimed is:

1. A perspiration inhibiting or retarding preparation consisting essentially of zinc sulfamate as the essential anti-perspirant ingredient in an effective amount from about 5 to 60% by weight, surface active material having a long aliphatic chain, and water.

2. A cosmetic preparation consisting essentially of oleaginous phase, an aqueous phase having zinc sulfamate dissolved therein in an effective amount from about 5 to 60% by weight to inhibit or retard perspiration when the preparation is applied to human skin, and surface active material to hold said phases in stable emulsion, said surface active material having a long aliphatic chain.

3. A cosmetic preparation for inhibiting or retarding perspiration comprising an emulsion of an oleaginous phase containing fatty material and an aqueous phase containing zinc sulfamate

as an anti-perspirant ingredient in an effective amount from about 5 to 60% by weight of the cosmetic preparation.

4. A cosmetic preparation in the form of a cream emulsion for inhibiting or retarding perspiration comprising a cream emulsion of an oleaginous phase held in dispersion in an aqueous phase, an acid stable emulsifying agent therefor to maintain said emulsion, and as an essential anti-perspirant ingredient zinc sulfamate in an effective amount from about 5 to about 60% by weight in solution in said aqueous phase.
